UNITED STATES PATENT OFFICE

RICE OWEN CLARK, OF VANCOUVER, BRITISH COLUMBIA, CANADA

CARBURETOR

Application filed December 8, 1928, Serial No. 324,756, and in Canada December 28, 1927.

My invention relates to improvements in carburetors which are particularly adapted for use in vaporizing heavy hydrocarbons for consumption in internal combustion engines. The particular objects of the invention are to provide means whereby an abundance of controllable heat may be utilized from the exhaust of an engine to bring the fuel oil up to such a temperature that the tension of the intake will cause the oil to be reduced to a state of high division, so that the resulting oil vapour may be readily and completely consumed within the engine cylinder; to provide means for regulating the supply of such heat to conform to the evaporation requirement of oils of different gravities without causing carbon deposit on the walls of the vapour chamber and passages, and to provide for a complete vaporization without increasing the vapour tension beyond that which is permissible to maintain the full volumetric efficiency of the engine. A still further object is to provide means whereby two or more liquids may be supplied for the production of a suitable combustible gas in a single chamber.

The invention consists essentially of a vaporizing chamber surrounded with one or more ducts or tubes through which exhaust gases and fresh air are admitted, the latter being in part directed, after being heated by the exhaust gases, into the vaporizing chamber where it combines with the liquid fuel and is brought to a state of high division suitable for combustion purposes, as will be more fully shown in the accompanying drawings and described in the following specification, in which:—

40 Fig. 1 is a general sectional view of the invention arranged with a multiple feed for the utilization of different liquids.

Fig. 2 is a modified sectional view of the invention.

45 In the drawings like characters of refer-

ence indicate corresponding parts in each figure.

The numeral 1, see Figure 1, indicates generally a cylindrical body having inlet and outlet passages respectively numbered 2 and 3, which are adapted to be interposed between an internal combustion engine exhaust and its muffler. Fitted to the ends of the body 1 are flanges 4 and 5 respectively which serve to support between them an inner cylinder 6, thus forming an annular passage 7 through which the exhaust gases flow, this passage is provided with one or more baffles 8 to increase the gas travel. The lower flange 5 is provided with radial projections 9 between which free air inlets 10 are defined. A head 11 is carried upon the flange 4, which head is centrally apertured to receive a tubular vaporizing chamber hereinafter referred to, and is provided with a plurality of concentrically disposed apertures 12 for the introduction of auxiliary air, these apertures 12 are adapted to be opened or closed by a correspondingly apertured flange 13 which is adapted to be moved as desired by any suitable manual means. A cylindrical jacket 14 encircles the head 11 and the flanges 5 to which it is secured, so as to produce an annular passage 15 through which auxiliary air flows to intermingle with the air admitted through the apertures 12 of the head 11, thence flowing downwards into an annular space 16. Secured to the underside of the flange 5 is a base 17 having a bottom closure 18, an inner annular wall 19 and an outer annular wall 20.

The inner annular wall is provided with one or more openings 21 each of which is fitted with an automatic flap valve 22. Extending upwards from the inner wall 19 through the flanges 5 and 4 and the head 11 is a vaporizing chamber 23 which is fitted internally with a plurality of collars 24 having a bore tapering inwards from opposite ends. Fitted to the base 17 is a fitting gen-

erally indicated by the numeral 25 having a central passage 26 extending upwards through an upstanding stem 27 and one or more needle controlled jets 28 communicating with said passage and leading from a suitable fuel supply through unions 29. A hot air connection 30 is made from the annular space between the walls 19 and 20 and the base of the central passage 26. Suitably supported concentrically within the vaporizing chamber 23 and preferably adjustable as to vertical position is a rod 31 having a plurality of inverted cones 32 spaced therealong which are so disposed as to be suspended intermediate the collars 24, which cones are of such a diameter at their base as to leave annular spaces thereabout of equal or greater cross sectional area than the spaces between the rod 31 and the smallest internal diameter of the collars 24 so as to prevent any choking tendency to the gases passing upwards through the chamber 23. The lower extremity of the rod 31 is fitted into the upper end of the passage 26 and is tapered as at 33, such tapered end being adapted to rest adjacent one or more cross passages 34 extending through the stem 27.

In the modification shown in Figure 2, a head 35 is provided having an annular wall 36 containing exhaust gas inlet and outlet apertures respectively numbered 37 and 38, an upper end closure 39 and a bottom closure 40 which is outwardly flanged as at 41. An apertured division wall 42 extends transversely of the head 35 and is fitted with a butterfly throttle 43 which may be opened to by-pass the exhaust gas directly or in part from the inlet 37 to the outlet 38 so as to reduce the amount of heat transmitted to the several parts if desired. A transverse passage 44 extends from the vertical centre of the head to its outer wall which communicates with the intake manifold of the engine and is preferably fitted with a throttle 45. Radially disposed apertures 46 and 47 respectively are formed in the bottom closure 40, the former being provided for the passage of exhaust heat from and to the head 35 while the latter are for the admission of fresh air to the vaporizing chamber 23. A base 48 substantially similar to the bottom closure 18 shown in Figure 1, is provided, having a central chamber 49 between which base, central chamber and the bottom closure 40 three concentrically arranged cylinders respectively numbered 50, 51 and 52 are mounted, the space numbered 53 between the cylinder walls 50 and 51 forming a fresh air passage, the space 54 between the cylinder walls 51 and 52 being an exhaust gas passage and the space within the cylinder 52 forming the vaporizing chamber 23. A venturi 55 is formed at the base of the vaporizing chamber 23 in which an annular jet 56 having a conical spreader 57 is con-

centrically disposed, which jet is connected to a suitable fuel line 58.

At the base of the cylinder 50 is a plurality of apertures 59 which are adapted to be exposed or covered by an apertured band 60 which is adapted to be moved circumferentially about the cylinder 50 by any suitable manual means, not shown. Communicating passages 61 are provided between the space 53 and the central chamber 49 and its venturi 55. Baffles 62 extend vertically of the passage 54 for the purpose of directing the flow of exhaust gases throughout a length equivalent to that of the vaporizing chamber 23.

Having thus described the several parts of my invention I will now briefly explain the function of same as shown in Figure 1.

The engine draws free air through the inlet apertures 10 into the outer chamber 15 which on flowing to the chamber 16 is supplemented by air entering the apertures 12, the auxiliary supply being controlled manually by movement of the apertured flange 13. The air thus induced is brought into contact with the walls of the exhaust passage 7 and is heated to a desired temperature before it passes through the opening 21 and into the vaporizing chamber 23. Some of the heated air is passed through the pipe 30 and caused to flow directly across the fuel jet 28 which serves to break up the fuel into finely divided globular form, the remainder of such air enters the vaporizing chamber adjacent the cross passages 34 thus bringing the fuel into a state of high division, which is still further divided in its upward flow whilst diverging and converging past the cones and collars 32 and 24 respectively.

It will thus be seen that the fuel is subjected to a primary and a secondary division due to air currents which in the case of heavy fuels is highly beneficial and produces a mixture which is readily combustible in engines which were designed to use gasoline alone.

What I claim as my invention is:

1. The combination with a liquid fuel jet, of a vaporizing chamber adapted to be connected to an engine manifold and having air inlet, said chamber having spaced constrictions at some intervals of its length and concentrically disposed cones at other intervals, an air inlet passage surrounding said vaporizing chamber, and an exhaust gas passage surrounding the air inlet passage.

2. In a carburetor, three concentrically arranged passages the outermost of which is adapted to serve as an exhaust gas jacket for the others, the intermediate passage being open to the atmosphere at one end and in communication with the inner passage at the opposite end, said inner passage forming a vaporizing chamber and having a liquid fuel jet at one end, means causing the gas

to diverge and converge in its flow through the chamber, said means comprising a plurality of internally tapered collars at regular intervals of the passage, and a plurality of centrally supported inverted cones alternately spaced between the collars.

3. In a carburetor as claimed in claim 2 wherein a fuel jet is arranged to feed fuel into the cylindrical body and means are provided for passing heated gases across the mouth of said jet prior to the delivery of the fuel to the cylindrical body.

Dated at Vancouver, B. C., this 1st day of December, 1928.
